PAPER-CUTTING MACHINE SPACING
MECHANISM

Mortimer Sendor, New York, N. Y.

Application December 11, 1941, Serial No. 422,471

9 Claims. (Cl. 164—59)

This invention relates to improvements in preferably power driven paper cutters and particularly with spacing mechanism capable of arrangement to define or determine the cutting positions for a given series of cuts and for repetition of the same series of cuts.

One of the objects of the invention is the provision of simple, inexpensive, sturdy and accurate mechanism attachable with a number of types of old and new style cutters and having means for cooperative or independent non-interfering operation relative to the machine mechanism.

Another object of the invention is the provision of mechanism of the kind stated arrangeable for cuts quite close together and for trim cuts as well as main cuts.

Another object is the provision of means for manual actuation of the spacing mechanism to lockingly clear the stops when a cut is made to permit the operator to operate the back gauge feed to the next desired position of cut.

Still another object is the provision of stop adjusting means to compensate for wear of the contacting surfaces of the stops.

These and other objects will be readily understood from the following description and attached drawings in which

Fig. 1 is a perspective view of my novel spacing mechanism mounted on a paper cutter table with parts broken away.

Fig. 2 is a cross section view of my bar and stops taken on line 2—2 of Fig. 3.

Fig. 3 is a fragmentary plan view of my device showing my bar and stops and gauge finger.

Fig. 4 is an elevation view partly in section, looking at the front of a paper cutter machine showing my device mounted on the table with parts of the machine broken away.

Fig. 5 is a side elevation view partly in section of my spacing mechanism control crank handle and its locks taken on line 5—5 of Fig. 4.

Fig. 6 is a side elevation view of an embodiment of my stops showing the adjustably mounted contacts on the finger engaging side of the stops.

Fig. 7 is an elevation view of an embodiment of my stop bar showing means for slideably adjusting its position relative to the table and table mount elements.

Fig. 8 is a perspective view of one of my stops showing right hand type finger-engaging-lip element 212.

My invention is shown in Figs. 1 and 4 applied to a paper cutter of more or less conventional design comprising a work table 11, having suitable

base standards (not shown) a back gauge 13 and a knife bar 14. Conventional means 15, driven by a motor (not shown), for actuating said knife up and thence down in which latter stroke the knife is drawn simultaneously across the paper stock, are schematically shown in part and may comprise mechanism such as described in Patent Number 464,202, wherein a driven crank shaft having crank pins which are joined by connecting rods with the knife ends, cause the knife to descend, make its cut, and ascend to its topmost position.

A pressure clamp (not shown) is usually provided on such machines to hold the paper P while it is being cut.

The back gauge 13, as in Fig. 1, travels forward feeding the paper to the knife or backwards without the paper in the usual manner, and has projection 16, extending downward through a slot 17 in the table, which projection 16 is joined to a belt 18 that runs as shown, on forward 19, and rearward wheel (not shown) supported upon the underside of the table. Said projection has finger 20 engageable with stops 21. The forward wheel 19 is mounted to turn with a hand wheel 22 by means of which the belt 18 is caused to travel for propelling the back gauge 13 forwardly toward wheel 19, and backwardly away from the wheel.

On preferably the left side of said finger 20 I mount on the table, by suitable means 23, a turnable rod 24 which carries a number of removably mounted and spaced apart top and bottom posts or stops 21. Said rod has longitudinal grooves 241 to receive screw ends 251 therein to facilitate guide of the stops along the rod and removable locking engagement of the stops with the rod.

Fixed on one end of rod 24 is lever 26 having end 261 in pivotal connection with one end of rod 27, the other end of the latter rod being in turn pivotally connected at 281 with lever 28 the latter being fixed on rod 29. Member 29 is mounted to turn in suitable means 30, 30a in turn removably mounted on the table 11 by screws 30b (see Fig. 4).

The forward end 291 of rod 29 has fixed thereon, one end 311 of control hand crank 31. The free end 312 of member 31 is limited in its arcuate movement by stops 32 on forward member 30 as shown in Figs. 1 and 4 to limit the movements of stops 21 as will be seen. It is seen that clockwise movement of crank 31 moves rod 24 clockwise and that anti-clockwise movement of crank 31 moves rod 24 anticlockwise. Forward member 30 may be provided with preferably 3

detents 301, 302 and 303 to selectively receive the ball of hand crank automatic set-mechanism 33 shown in Figs. 4 and 5, so that rod 24 and its stops 21 may be held in a desired set position relative to finger 20. Member 33 may comprise a housing having a spring actuated ball 34 the compression of which spring is increased when the screw 35 is moved inwardly toward the ball 34. When the ball sets in detent 301 the bottom stops 21 are engageable with the finger. Within the ball in detent 303 as in Figs. 1 and 4, the top stops 21 are engageable with the finger. The lever 31 may have mounted thereon a pin 37 which may engage one of ports 304, 305, 306 in the same radial lines respectively as indents 301, 302, 303 of member 33 to more positively engage the lever 31 with member 30. The pin is more frequently used to engage the central port 305 to maintain the stops 21 in neutral unengageable position as in Fig. 2. At times only indents 301, 303 and port 305 are provided. A handle 38 is mounted on free end of lever crank 31.

In the embodiment of Fig. 6 is shown a pair of stops 21a each having a screw 211 mounted thereon and held by set screw 212. The head of member 211 is arranged to contact the finger 20 presenting adjustable contact means. The contacting surface of stops not having such screws 211 are known to wear. It is seen that the position of the head of screw 211 can be adjusted to compensate for wear by releasing the set screw 212 and turning the head screw.

In operation the spaces between the cut lines of the paper P are determined and the spacing S required between the stops conforming with the spacing between the cut lines is provided by setting the stops 21 on the bar 24, in accordance with the cut line determination. The finger contacting surface 211 of the most forward stop is usually set to contact the finger 20 at the point where the knife 14 contacts the paper for the most forward cut, the paper being in clamped position on the table. Once the paper has been cut along said line, by engagement of a main clutch to produce a revolution of the crank shaft causing the knife to descend, make the cut and ascend, the now unclamped remaining paper is moved forwards on the table by anticlockwise movement of wheel 22. Of course the gauge and paper move forward only after the stops 21 are placed in neutral position (see Fig. 2) permitting forward unobstructed movement of the finger 20 past the stops 21.

Movement of crank 31, engaging ball 34 in detent 302 places the stops in neutral position. As the second cut line on the paper approaches the knife edge line the second most forward stop is swung into finger engaging position, its surface 211 to contact the finger surface 201 when the cut line of the paper coincides with the knife edge line. Said second stop may be mounted on the upper part and groove of bar 24 or on the lower groove. Where paper trim cuts, close together and narrower than the width of a stop or stop lip 212, are necessary, I prefer to set the contacting surface of the lower stop a distance equal to the width of the trim, to the front of similar contacting surface of the upper stop. Various arranged position of stops are seen possible. At times stops arranged merely on the top rail are adequate to provide the spacing for the necessary series of cuts of paper. Stacks of sheets having gang printed labels thereon usually require that stops be placed on both top and bottom parts of the grooved bar to efficiently

cut the gang printed sheets into the many labels printed on each sheet.

Fig. 8 shows a perspective of a right hand type stop block having finger engaging lip 212 and contacting surface 211a. It is understood that such a lip may be left hand type as shown in Fig. 3.

To provide unitary longitudinal adjustment of the rod with its mounted stops in Fig. 7 is seen 10 an embodiment of a rod 24 having elongated rear and front ends 245, 246 for slideable engagement in front and rear members 23. End 245 is threaded for nut 247. Spring 248, flexing against shoulder 244 and member 26, normally 15 maintains the rod forwardly. Turning the nut 247 clockwise moves rod 24 and its mounted stops rearwardly against the normal action of spring 248.

Having thus described my invention, its utility 20 and mode of operation, what I claim and desire to secure by Letters Patent of the United States is:

1. In a machine of the class described, a finger 25 movable with the work, a rectangular grooved rod journaled on said machine parallel with the line of work travel, stops fixedly carried by said grooved rod with respect to the work travel and engageable with said finger, a shaft journaled on said machine and connected at one end to said 30 grooved rod by means of links to control the angular position of the grooved rod, means on the other end of the shaft to manually rock said shaft to engage a selected stop and finger to hold the work and to disengage same to advance the work.

2. The device of claim 1 including latching 40 means on said rock means engageable with the machine to lock the shaft in position to hold the stop in the desired position.

3. The device of claim 1 in which the stops are 45 movably mounted on said rod to gauge different positions of the work for a series of operations thereon, said positions being variable from nil to maximum.

4. The device of claim 1 including means to 50 adjust the finger engaging surface of said stops comprising a turnable screw mounted on said stops.

5. The device of claim 1 including means to 55 adjust the finger engaging surface of said stops comprising a turnable screw mounted on said stops, and means to lock said screw in its adjusted position.

6. The device of claim 1 including means on 60 said rod to move it independently in the direction of finger travel comprising ends on the rod slideable in said journals, a spring having one end engaged with the rod and another end engaged with the machine flexibly tending to slide the rod in said journals against the action of a turnable nut on an end of the rod engaged with the machine.

7. The device of claim 1 in which said spacing 65 mechanism is demountable and independent of the machine.

8. The device of claim 1 including means for 70 fixing said stops on said rod comprising a screw in the stop engageable with said rod's grooved portion whereby partial release of the screw permits slide of the stop on the rod and full release of the screw permits separation of the stop from the rod.

9. In a machine of the class described, a finger 75 movable with the work, a rectangular fluted rod

journalized on said machine parallel with the line of work travel, stops carried by said fluted rod with respect to the work travel and engageable with said finger, a shaft journaled on said machine and connected at one end to said fluted rod by means of links to control the angular position of the fluted rod, means on the other end of

the shaft to manually rock said shaft to engage a selected stop and finger to hold the work and to disengage same to advance the work, and latching means on said rock means engageable with the machine to lock the shaft in position to hold the stop in the desired position.

MORTIMER SENDOR.
